United States Patent Office.

WILLIAM P. ADAMS, OF BROOKLYN, NEW YORK.

Letters Patent No. 97,851, dated December 14, 1869.

IMPROVED IRONING-TABLE AND CLOTHES-DRIER.

The Schedule referred to in these Letters Patent and making part of the same.

To all whom it may concern:

Be it known that I, WILLIAM P. ADAMS, of Brooklyn, in the county of Kings, and State of New York, have invented a new and useful Improvement in Combined Ironing-Table and Clothes-Drier; and I do hereby declare that the following is a full, clear, and exact description thereof, which will enable others skilled in the art to make and use the same, reference being had to the accompanying drawings, forming part of this specification.

This invention relates to a new and useful improvement in an article for the laundry, and consists in an adjustable ironing-table, and, in combination therewith, a clothes-drier; arranged as hereinafter more fully described.

The accompanying drawing represents a perspective view of the article.

Similar letters of reference indicate corresponding parts.

A is the frame or stand, consisting of two uprights B B, connected together by the horizontal rail C, and mortised into the foundation-pieces D D.

On the top of the uprights B B are cap-pieces E E, secured firmly thereto, which support the ironing-board F. This ironing-board is pivoted to one of the cap-pieces, from which it may be removed or swung round on its pivot, so as to admit skirts or other garments. For ironing either skirts or other articles, it is supported by both the caps E E, and forms the ironing-table.

G is an extension clothes-drier, which is connected with the ironing-table by the bars H H. These bars are pivoted to the stands B B, but are rigidly attached to the clothes-drier.

Connected in this manner, it will be seen that the drier may be placed in different positions for use.

As represented in the drawing, the rounds I of the drier stand nearly in a vertical position, and the drier is supported by the slats J J, which are pivoted to the sides of the drier.

The drier is made in three sections.

K K are the sides of the main section, which have

rounds I extending from one to the other, made fast thereto.

M M represent the sides of the movable sections, which slide on the rounds of the main section, and whose rounds N pass through holes in the sides K K, intermediately between the stationary rounds I.

It will be seen that the sides M M, when moved from the centre in each direction, will elongate the drier, and their rounds N will project as seen in the drawing.

By removing the table or ironing-board F entirely from the frame A, the bars H H are made to take an upright position, while the clothes-drier will occupy a horizontal position.

The drier is secured in this position by means of buttons o on the uprights B B.

When the ironing-table F is in place, (on both the caps E,) its unpivoted end is kept in position by buttons on the cap, as seen at P.

When the sliding sections of the drier are moved inward to the centre, the ends of the rounds N will not project, but be flush with the sides K. In this position the slats J J are turned up so as to cover the outer sides of K K, and are kept in that position by a dovetail, as seen at Q.

By this arrangement the apparatus for ironing and drying clothes is always at hand, the ironing-table and ironing-board being essentially the same thing.

The advantages of this arrangement will be readily understood and appreciated by all housekeepers.

Having thus described my invention,

I claim as new, and desire to secure by Letters Patent—

1. The extension clothes-drier G, constructed and operating as described, for the purpose set forth:

2. The combination of the clothes-drier G and the frame A and ironing-board F, as and for the purposes set forth.

WM. P. ADAMS.
